CLAIM

The ornamental design for a steering wheel with a display for an industrial vehicle, as shown and described.

DESCRIPTION

FIG. 1 is a front, top, and right side perspective view of a steering wheel with a display for an industrial vehicle showing my new design;

FIG. 2 is a front, bottom, and left side perspective view thereof;

FIG. 3 is a front view thereof;

FIG. 4 is a rear view thereof;

FIG. 5 is a top plan view thereof, the bottom plan view being a mirror image of FIG. 5;

FIG. 6 is a right side view thereof; and,

FIG. 7 is a left side view thereof.

The broken lines illustrate portions of the steering wheel with a display for an industrial vehicle that form no part of the claimed design.
